FURNACE PULL-OUT APPARATUS

Charles Palmer and Edgar G. Woodward, Worcester, Mass., assignors to Morgan Construction Company, Worcester, Mass., a corporation of Massachusetts

Application February 15, 1952, Serial No. 271,736

8 Claims. (Cl. 214—18)

This invention relates to furnace pullout apparatus and more particularly to a device for removing hot metal bars from a furnace and introducing them into a rolling mill.

In the rolling of metal billets and bars, it is customary to heat them in a gas or oil fired furnace to the required rolling temperatures before passing them into the rolling mill. When the bar has reached the discharge end of the furnace, it is pushed lengthwise through a small doorway in the side of the furnace. The protruding end of the bar is grasped between two pinch rolls. The pinch rolls pull the bar out of the furnace and introduce it into the rolling mill. In the past these rolls have been mounted on the furnace structure over the discharge doorway. In this position they were subject to the expansion and contraction movement of the furnace and to the high temperatures of the furnace gases emitted through the doorway, whereby high maintenance costs were experienced. Now, it is often desirable to be able to have clear access to the discharge door in order to clean out the furnace or to remove bars which, for one reason or another, cannot be pushed out in the ordinary way. With the prior art devices it has been difficult, if not impossible, to clear the discharge door for access thereto. Furthermore, it was not possible to adjust the pinch roll gap or pressure to accommodate various sizes and types of bar under various conditions. The present invention obviates these difficulties of the prior art in a novel manner.

It is therefore an outstanding object of the present invention to provide a pullout roll apparatus which can be easily removed from the discharge door of a furnace for access thereto.

It is another object of this invention to provide pinch rolls for moving bars longitudinally, wherein the spacing and pressure between the rolls is controllable and adjustable.

A further object of this invention is the provision of a furnace pullout apparatus in which the rolls may be easily and conveniently separated.

Still another object of the invention is to provide a furnace pullout apparatus having an upper roll portion which may be moved horizontally or vertically away from the remainder of the apparatus and which can be securely locked in operative position.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Figure 1 is a plan view of the apparatus of the invention.

Figure 2 is an elevation view of the invention looking toward the furnace,

Figure 3 is a view of the invention taken on the line 3—3 of Figure 1.

Like reference characters refer to similar parts in the several figures of the drawings.

Referring first to Figure 1, which best shows the general features of the invention, the pullout apparatus, generally designated by the reference character 10, is shown mounted on the floor of a mill in front of a furnace 11. The furnace 11 is of a well-known type for heating bars prior to their passage through a rolling mill and it comprises a refractory wall 12 supported by vertical beams 13 and horizontal beams 14. A discharge door 15 passes through

2

the refractory wall to permit the passage of heated bars therethrough. The pullout apparatus 10 consists of a base 16 extending parallel to the furnace wall adjacent the door 15 and an upper member 17 mounted thereon. 5 A motor base 18 is mounted on the floor some distance from the base 16 and has a motor 19 fixed thereto and driving a gear reduction apparatus 20. The apparatus 20 is, in turn, connected to a drive shaft 21 which is coupled to the apparatus in a manner to be described hereinafter.

Referring next to Figure 2, the base 16 is shown as an elongated rectangular member having ways 22 on which the upper member 17 rests for sliding movement in a direction parallel to the furnace wall. The base 16 and the upper member 17 are connected for movement relative to one another by a hydraulic jack 23, the cylinder 24 of which is connected to a bracket 25 on the base 16 and the piston rod 26 of which is connected to a bracket 27 on the underside of the upper member 17. A hold-down block 28 is attached to the base 16 and a similar block 29 is fastened to the upper member 17; these blocks have mating inclined faces which engage and clamp the upper member downwardly on the base 16 when it is in operative position before the furnace door. The fixing of the upper member in operative position is further carried out by the provision of a wedge apparatus 30. This apparatus consists of a lower projection 31 which is a part of the upper member 17, an upper projection 32 which is a part of the base 16, and a wedge 33. The two projections are provided with grooves for guiding the wedge and it can be seen that driving the wedge between the projections will draw the upper member downwardly onto the base 16. The grooves for holding the wedge are inclined as shown in the drawing so that driving the wedge 33 serves the further purpose of moving the upper member to the right in Figure 2 along the base and causing the inclined faces of the blocks 28 and 29 to slide along each other and pull the upper member downwardly onto the base 16.

40 Referring next to Figure 3, the base 16 is provided with an upstanding pedestal 34 along the side adjacent the furnace and at the top of the pedestal is mounted an elongated bottom roll 35. The roll 35 is mounted horizontally in bearings 36 and is connected to and driven by the drive shaft 21. The uppermost portion of the roll 35 is at the hearth line of the furnace or slightly thereabove. A top roll 37 is mounted over the bottom 35 on a horizontal axis parallel to that of the bottom roll; the top roll is rotatably held at its ends in bearings 38 at one end of an arm 39. The arm 39 is coextensive with the roll and consists of a broad web 40 having vertical strengthening flanges 41. The arm 39 is keyed to a shaft 42 which is spaced rearwardly and upwardly from the bottom roll 35 and is mounted in bearings 43 which are fixed to the upper member 17. The shaft 42 extends through and beyond the bearing on the motor side of the apparatus and to this extension is keyed a crank arm 44 which is pivotally attached near its other end to a piston rod 45 of a pneumatic motor 46. The motor 46 has pivot pins 47 extending from its sides in such a manner that their axes are aligned and pass through the center of gravity of the motor. The pins 47 are mounted in bearings 48 fastened to the upper member 17, so that the motor is free to rotate slightly about the axis of the pins. The extreme end of the crank arm 44 has a threaded bore 49 passing therethrough in a direction perpendicular to the axis of the bottom roll and through this bore is threaded a bolt 50 having its head positioned away from the furnace; a stop 51 is formed on the upper member 17 in a position to be engaged by the head of the bolt 50 in its rearward movement. A guide trough 52 is provided beneath the arm 39 and the shaft 42 and extending rearwardly of the rolls 35 and 37.

75 In the operation of the apparatus, a bar passes broadwise through the furnace 11 and finally arrives in heated condition opposite the door 15. It is pushed longitudinally through the door and passes between the rolls 35 and 37. The bottom roll 35 is driven by the motor 19, while the top roll 37 is an idler. Both rolls may have serrated surfaces in order that they may grasp the bar more securely. The top roll 37 is moved downwardly

into engagement with the bar by the actuation of the pneumatic motor 46; the piston 45 is drawn into the motor, thus moving the lower end of the crank arm 44 rearwardly until the head of the bolt 50 strikes the stop 51. Generally speaking, the top roll 37 strikes the bar before its downward movement is stopped by the bolt 50 striking the stop 51 and the roll separating forces are absorbed by the pneumatic motor 46. In other words, the top roll 37 is pressed downwardly on the bar by the motor 46 and this causes the bar to be clamped between the rolls and moved therethrough by the driving of the bottom roll 35. The position of the top roll will vary with the thickness of the rod and, of course, this means that the roll pressure will be constant regardless of irregularities in the bar, etc. After the bar passes through the rolls, it slides along the trough 52 and from there enters the rolling mill, a switching means, or a runon table depending upon the particular mill arrangement. It is desired to clear the neighborhood of the furnace door so that the furnace can be cleaned or so that difficulties in the furnace can be cleared up, the upper member 17 along with the top roll 37 and associated apparatus may be moved along the base 16; this is done by removing the wedge 33 and then actuating the hydraulic jack 23. The base 16, with its pedestal 34 and the bottom roll 35 remain behind, but they are below the bottom edge of the furnace door and do not interfere with the use of cleaning rods and the like.

While certain novel features of the invention have been shown and described and are pointed out in the annexed claims, it must be understood that various omissions, substitutions, and changes in the forms and details of the device illustrated and in its operation may be made by those skilled in the art without departing from the essence of the invention.

The invention having thus been described, what is claimed as new and desired to secure by Letters Patent is:

1. A furnace pullout apparatus, comprising: a base, a horizontal bottom roll rotatably mounted on said base, a motor connected to the bottom roll for the driving thereof, an upper member mounted on said base for sliding motion parallel to the axis of said bottom roll, a top roll rotatably mounted parallel to the bottom roll on said upper member and overlying said bottom roll, said top roll being capable of movement toward and away from the bottom roll, and means mounted on said upper member for moving the top roll toward and away from the bottom roll.

2. A furnace pullout apparatus, comprising: a base, a horizontal bottom roll rotatably mounted on said base, a motor connected to the bottom roll for the driving thereof, an upper member mounted on said base and capable of sliding motion relative to the base parallel to the axis of said bottom roll, means for locking the upper member and the base together, a top roll rotatably mounted on said upper member parallel to the bottom roll and overlying said roll, said top roll being capable of movement toward and away from the bottom roll, means mounted on said upper member for moving the top roll toward and away from the bottom roll, and means limiting the movement of the top roll toward the bottom roll.

3. An apparatus as recited in claim 2, wherein: the means for locking the upper member and the base together comprises projections on the member and base having inclined mating surfaces.

5. An apparatus as recited in claim 2, wherein: the means for locking the upper member and the base together comprises projections on the member and base and a wedge extending therebetween.

10. An apparatus as recited in claim 2, wherein: the means mounted on said upper member for moving the top roll toward and away from the bottom roll comprises a pneumatic motor.

15. A pullout apparatus for use in drawing bars and the like from the discharge door of a furnace, comprising: a base fixedly mounted in front of the said door, a horizontal bottom roll rotatably mounted on said base on a level with the bottom edge of the door, a motor connected to the bottom roll for the driving thereof, an upper member mounted on said base for sliding motion relative

20. to the base parallel to the plane of the furnace door, means for actuating said motion between the upper member and the base, means for locking the upper member in position on the base in front of the door, a top roll rotatably mounted on said upper member parallel to the bottom roll and overlying said bottom roll, said top roll being capable of movement toward and away from the bottom roll, means mounted on said upper member for moving the top roll toward and away from the bottom roll, and means limiting the movement of the top roll

25. toward the bottom roll.

6. A furnace pullout apparatus, comprising: a driven horizontal bottom roll having a fixed position relative to the furnace, an idler top roll mounted parallel to the bottom roll, an arm mounted for pivotal motion about one end, said top roll being journaled in the other end of the arm on an axis parallel to the axis of the top roll and overlying the bottom roll, and a pneumatic motor for actuating said pivotal motion of the arm to carry the top roll toward and away from the bottom roll.

7. A furnace pullout apparatus, comprising: a driven horizontal bottom roll, an idler top roll mounted parallel to the bottom roll, an arm, a shaft rotatably mounted on an axis parallel to the axis of said bottom roll, said arm being pivotally mounted at one end on said shaft, the top roll being journaled in the other end of said arm so as to overlie the bottom roll, a crank arm attached at one end to said shaft, a pneumatic rotor attached to the other end of said crank arm for the actuation thereof, and means attached to said crank arm for limiting movement thereof.

30. 8. A furnace pullout apparatus, comprising: a driven horizontal bottom roll, an idler top roll mounted parallel to the bottom roll, an arm, a shaft rotatably mounted on an axis parallel to the axis of said bottom roll, said arm being pivotally mounted at one end on said shaft, the top roll being journaled in the other end of said arm so as to overlie the bottom roll, a crank arm attached at one end to said shaft, a pneumatic rotor attached to the other end of said crank arm for the actuation thereof, and means attached to said crank arm for limiting movement thereof.

35. 9. A furnace pullout apparatus, comprising: a driven horizontal bottom roll having a fixed position relative to the furnace, an idler top roll mounted parallel to the bottom roll, an arm, a shaft rotatably mounted on an axis parallel to the axis of said bottom roll, said arm being pivotally mounted at one end on said shaft, the top roll being journaled in the other end of said arm so as to overlie the bottom roll, a crank arm attached at one end to said shaft, a pneumatic rotor attached to the other end of said crank arm for the actuation thereof, and means attached to said crank arm for limiting movement thereof.

40. 10. A furnace pullout apparatus, comprising: a driven horizontal bottom roll, an idler top roll mounted parallel to the bottom roll, an arm, a shaft rotatably mounted on an axis parallel to the axis of said bottom roll, said arm being pivotally mounted at one end on said shaft, the top roll being journaled in the other end of said arm so as to overlie the bottom roll, a crank arm attached at one end to said shaft, a pneumatic rotor attached to the other end of said crank arm for the actuation thereof, and means attached to said crank arm for limiting movement thereof.

45. 11. A furnace pullout apparatus, comprising: a driven horizontal bottom roll, an idler top roll mounted parallel to the bottom roll, an arm, a shaft rotatably mounted on an axis parallel to the axis of said bottom roll, said arm being pivotally mounted at one end on said shaft, the top roll being journaled in the other end of said arm so as to overlie the bottom roll, a crank arm attached at one end to said shaft, a pneumatic rotor attached to the other end of said crank arm for the actuation thereof, and means attached to said crank arm for limiting movement thereof.

50. 12. A furnace pullout apparatus, comprising: a driven horizontal bottom roll, an idler top roll mounted parallel to the bottom roll, an arm, a shaft rotatably mounted on an axis parallel to the axis of said bottom roll, said arm being pivotally mounted at one end on said shaft, the top roll being journaled in the other end of said arm so as to overlie the bottom roll, a crank arm attached at one end to said shaft, a pneumatic rotor attached to the other end of said crank arm for the actuation thereof, and means attached to said crank arm for limiting movement thereof.
